(57) **CLAIM**

The ornamental design for a waveguide orthomode transducer, as shown and described.

DESCRIPTION

FIG. 1 is a perspective view of a waveguide orthomode transducer design showing my new design.

FIG. 2 is a front view of a waveguide orthomode transducer.

FIG. 3 is a rear view of a waveguide orthomode transducer.

FIG. 4 is a right side view of a waveguide orthomode transducer.

FIG. 5 is a left side view of a waveguide orthomode transducer.

FIG. 6 is a top view of a waveguide orthomode transducer; and,

FIG. 7 is a bottom view of a waveguide orthomode transducer.

Any shading and cross-hatching are not features of the design but are utilized to illustrate the surface contours of the waveguide orthomode transducer design in the drawings. The broken lines depict portions of the waveguide orthomode transducer that form no part of the claimed design.
